UNITED STATES PATENT OFFICE

121,646

DESIGN FOR AN INFANT'S JACKET OR SIMILAR ARTICLE

Dorothy Ball Campbell, Washington, D. C.

Application June 6, 1940, Serial No. 92,861

Term of patent 7 years

To all whom it may concern:

Be it known that I, Dorothy Ball Campbell, a citizen of the United States, residing in the city of Washington, District of Columbia, have invented a new, original, and ornamental Design for an Infant's Jacket or Similar Article, of which the following is a specification, reference being had to the accompanying drawing, forming part thereof.

In the drawing, Figure 1 is a front view of the infant's jacket, showing my design, and Fig. 2 is a back view thereof.

What I claim is:

The ornamental design for an infant's jacket or similar article, as shown.

DOROTHY BALL CAMPBELL.
